UNITED STATES PATENT OFFICE.

JAKOB VELCANSKY, OF IRWIN, PENNSYLVANIA.

NOODLE-CUTTER.

1,176,257.

Specification of Letters Patent. Patented Mar. 21, 1916.

Application filed September 21, 1914. Serial No. 862,856.

To all whom it may concern:

Be it known that I, JAKOB VELCANSKY, a subject of the King of Hungary, residing at Irwin, in the county of Westmoreland and State of Pennsylvania, have invented 5 certain new and useful Improvements in Noodle-Cutters, of which the following is a specification, reference being had therein to the accompanying drawing.

10 This invention relates to noodle cutters and has for its object to provide a device of such class, in a manner as hereinafter set forth, including a cutter holder having provisions to permit of adjustably positioning 15 a series of cutters with respect to each other thereby enabling noodles of different widths to be cut.

Further objects of the invention are to provide a noodle cutter which is simple in 20 its construction and arrangement, strong, durable, efficient and convenient in its use, readily set up and comparatively inexpensive to manufacture.

With the foregoing and other objects in 25 view the invention consists of a novel construction, combination and arrangement of parts as hereinafter more specifically described and illustrated in the accompanying drawings wherein is shown an embodiment 30 of the invention, but it is to be understood that changes, variations and modifications can be resorted to which come within the scope of the claims hereunto appended.

In the drawings wherein like reference 35 characters denote corresponding parts throughout the several views:—Figure 1 is a perspective view of a noodle cutter in accordance with this invention. Fig. 2 is a perspective view, broken away, illustrating 40 the cutter holder open and free of cutters. Fig. 3 is a perspective view of a cutter. Fig. 4 is a detail of the holder.

Referring to the drawings in detail a noodle cutter consists of a holder comprising 45 a body portion 1 formed with a compartment 2 which is wedge-shaped in cross section. Pivoted to the body portion as at 3 is a closure 4 for the compartment 2 and said closure 4 has its free end formed with 50 a notch 5, to receive the resilient latch 6,

which is fixed as at 7 to one end of the body portion 1.

The front of the body portion is rounded as at 8 and is formed with a series of openings 9, which communicate with the compartment 2 and which are wedge shaped in contour. Extending through the compartment 2 and openings 9, are wedge-shaped cutters 10 which are maintained in position through the medium of the closure 4 when 60 the latter is swung to engagement with the latch 6. The openings 9 provide means to enable the positioning of the cutters 10 at different distances apart with respect to each other, under such conditions provision 65 is made for cutting noodles of different widths.

In setting up of the handle in a manner as stated provides for the convenient removal of a cutter when the occasion so requires or for substituting a new cutter for 70 a damaged one.

Secured to the back 11 of a cutter holder, is a handle 12.

What I claim is:—

1. A noodle-cutter comprising a body-portion having a plurality of spaced cutter-receiving apertures therein, a plurality of cutters adapted to be removably inserted in said apertures, whereby the spaced relation 80 of said cutters may be varied to vary the width of the strips cut, and a member hinged to said body-portion and abutting against the bases of said cutters for maintaining said cutters in position in said apertures. 85

2. A noodle cutter comprising a plurality of wedge-shaped cutters, a body portion having a plurality of spaced cutter-receiving apertures therein, said apertures 90 being of corresponding shape to said cutters, a member hinged to said body portion and abutting against the bases of said cutters for maintaining said cutters in position in said apertures, and a spring catch for 95 retaining said member in its abutting position, whereby the spaced relation of said cutters may be varied to vary the width of the strips cut.

3. A noodle-cutter comprising a plu- 100

rality of wedge-shaped cutters, a three-sided body having a plurality of spaced cutter-receiving apertures in one of the sides thereof, said apertures being of corresponding shape to said cutters, a handle on another side of said body, a member hinged to the third side of said body and arranged to abut against the bases of said cutters, and a spring catch for retaining said member in

its abutting position, whereby the spaced relation of said cutters may be varied to vary the width of the strips cut.

In testimony whereof I affix my signature in the presence of two witnesses.

JAKOB VELCANSKY.
